(57) **CLAIM**

The ornamental design for a busbar for battery cell, as shown and described.

DESCRIPTION

FIG. 1 is a bottom, front and right side perspective view of a busbar for battery cell showing our new design;
FIG. 2 is a top, rear and left side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof; and,
FIG. 8 is a bottom plan view thereof.

1 Claim, 8 Drawing Sheets
